UNITED STATES PATENT OFFICE.

EDWARD F. McCARTHY, OF CHICAGO, ILLINOIS, ASSIGNOR TO VACUUM MACHINERY CO., OF CHICAGO, ILLINOIS, A CORPORATION OF WISCONSIN.

COMBINED FEED-WATER HEATER AND ASPIRATOR.

1,382,104.

Specification of Letters Patent. Patented June 21, 1921.

Application filed January 21, 1918. Serial No. 213,114.

To all whom it may concern:

Be it known that I, EDWARD F. McCARTHY, a citizen of the United States, residing at Chicago, in the county of Cook and State 5 of Illinois, have invented certain new and useful Improvements in Combined Feed-Water Heaters and Aspirators, of which the following is a specification.

This invention relates to improvements 10 in a combined water heater and aspirator or suction pump, oil separator, condensation receiver and water purifier, and one of the objects of the invention is to construct a self-contained unitary apparatus of this character for the purpose of centralizing equipment and dispensing with considerable piping.

A further object is to provide an improved apparatus of this character by means 20 of which air and condensation may be drawn from steam systems in which a vacuum is employed, and is particularly adapted, though not necessarily limited in its use in return line vacuum heating or drying 25 systems in high pressure steam plants where condensation and air is drawn from the system through the medium of traps, directly to the aspirating device, which latter is preferably located at the top 30 of and inside of the apparatus, and in which apparatus the air and water are separated and the steam is condensed.

To the attainment of these ends, and the accomplishment of other new and useful objects as will appear, the invention consists in substantially the combination and arrangement 35 of the several parts hereinafter more fully described and claimed, and shown in the accompanying drawings illustrating this 40 invention, and in which:

Figure 1 is a vertical longitudinal sectional view of an improved apparatus of this character constructed in accordance with the principles of this invention and as 45 taken on the line 1-1, Fig. 2.

Fig. 2 is a vertical longitudinal sectional view as taken on line 2-2, Fig. 1.

Fig. 3 is a front elevation as taken from the left hand side of Fig. 1.

Referring more particularly to the drawings, the numeral 10 designates generally a closed tank or casing of any desired size and configuration and constructed and arranged within the tank preferably suspended from 50 the top 11 thereof is a hydro-turbine aspira-

tor embodying a chamber 12 suspended from the top 11 by suitable brackets or straps 13. This chamber or receptacle 12 is preferably open at the top and a second chamber or receptacle 14 telescopes with the chamber 12 60 and is also preferably suspended by means of brackets or hangers 15 from the top of the tank. The chamber 14 is somewhat larger than the chamber 12 and is spaced therefrom, the top of the chamber 14 preferably terminating below the top of the chamber 12 so that when the chamber 12 overflows, the water or liquid will pass into the chamber 14. The chamber 14 is provided for a purpose to be hereinafter described. 70

In order to clean the chambers 12 and 14, clean-out pipes 16, 17 are respectively connected with the bottoms of the chambers 12 and 14 and extend through the tank 10 and 75 communicate with a drain pipe 18. Valves 19, 20 are provided in the pipes 16, 17 to control such outlet. A suction tube or pipe 21 extends into the tank 10 and connects with the aspirator device through the bottom of the chamber 12, and in which chamber the aspirating device is located. The other end of the pipe 21 is connected with the system in which the vacuum is to be maintained. The aspirator comprises 80 preferably spaced disks 22, 23 which are separated from each other by means of upright partitions 24 and the parts are secured together in any suitable manner. Two of these partitions 24 are preferably provided 85 and are arranged diametrically opposite each other and the aspirator is secured to a shaft 25 of a motor 26, the latter being preferably mounted upon the top of the tank 10 so that the shaft and aspirator will be rotated by 90 the motor. Depending from the lower member 23 of the aspirator is a tubular element 27 journaled in a suitable bearing 28 and the pipe 21 has communication with the tubular member 27, thereby producing an aspirator of the type shown and described in 95 United States Patent No. 1,071,789, issued September 2, 1913, to Thomas O. Perry.

Disposed within the tank and below the receptacle 14 are a plurality of superposed 100 series of drip pans or trays 29, which are supported in any suitable manner, such as by means of suitable supports 30. These pans 29 are spaced from each other and the pans of the different series are staggered 110

with relation to each other so that when the water overflows from the chamber 14, it will flow successively into the pans 29 toward the bottom of the tank. In order to break the sheet of falling water into fine streams, the edges of the pans 29 are corrugated or serrated as at 31. Any number of these pans may be employed according to the size of the apparatus.

10 The lower portion of the tank 10 constitutes a water receptacle and is provided with an outlet 32 which leads to the pump or other point of use. Within this portion of the tank is a float 33, which latter is adapted 15 to control a valve 34 in an inlet pipe 35. The inlet pipe is provided for supplying the chamber or receptacle 12 with water and the discharge end 36 of this pipe is submerged in the receptacle 12 so as to prevent 20 hammering which always occurs when steam comes in contact with cold water. A controlling valve 37 may be provided in the pipe 35. Thus it will be seen that the water accumulating in the water receiving end or 25 chamber of the tank will control the movement of the float 33 and this float in turn controlling the valve 34, will control the height of water in the tank 10.

1 A sediment collector or mud ring 37 may 30 be provided in the tank so as to collect foreign matter from the water as it passes into the water receiving chamber.

A filter is also provided in the bottom of the tank and this filter preferably comprises 35 two sections 38, 39, preferably of a box-like formation, having imperforate side and end walls, with perforated or grated top and bottom walls 40, 41. Filtering material is placed within the filter chamber thus formed 40 and between the grated walls 40 and 41 and the filter is supported above the bottom of the tank in any suitable manner, such as by means of supports 42 and these supports 42 constitute a wall or flange projecting upwardly from the bottom of the tank and surrounding the outlet opening 32 so that in order that the water from the water chamber will pass through the outlet 32 it must pass through the filter by passing through 45 the top 40 and out of the bottom 41 thereof.

1 A sediment pan or receptacle 43 may be provided with a depending circumferential flange 44, which extends for a considerable distance below the bottom of the pan 43 and 55 this flange 44 is provided with openings 45 therethrough so that when the pan 43 and flange 44 are placed over the filter 40, the water will flow through the openings 45 to the top 40 of the filter. This flange 44 is 60 of any desired height, preferably so as to support the bottom of the pan 43 above and out of contact with the top of the filter 40 so as not to obstruct the passage of the water through the filter. Obviously this flange 44 65 may be constructed in the form of legs and

the pan is supported in any suitable manner, such as by means of the support 42.

The lower portion of the tank 10 is provided with a door or closure 46 removably secured in position to form a closure for the 70 opening 47, and this opening 47 is of a suitable size so as not only to permit access to the filter and pan 43 but also to permit of the removal thereof.

A clean-out opening 48, having a pipe 49 75 connected therewith and a controlling valve 50 in the pipe may be provided, whereby sediment may be cleaned from the bottom of the tank.

The tank is also provided with a similar 80 opening 51 adjacent the pans or trays 29 and a closure 52 is provided for the opening 51, so that when it is desired, the pans or trays 31 may be readily removed.

The water, as it flows from the receptacle 85 12, accumulates in the bottom of the tank, as will be manifest, and in the event that the discharge from the heater or tank through the outlet opening 32 is not as rapid as the accumulating water from the return 21 and 90 receptacle 12, the water in the heater or bottom portion of the tank will rise and eventually flow out of the heater through an outlet opening 53, and connected with this opening 95 53 is a U-shaped loop or trap 54, which has 95 connection with a chamber 55, leading from which chamber is a discharge pipe 56. This loop or trap 54 forms a water seal and prevents steam from escaping from the heater.

The exhaust steam is admitted into the 100 heater through an inlet pipe 57 which has communication with a chamber 58 and which chamber has an outlet 59 discharging into the tank 10. The outlet 59 is arranged adjacent the pans or trays 31, so that the incoming steam will be discharged against the streams of water flowing from the pans 31 to heat the latter and any steam which has not been condensed by its contact with the water or any vapor rising therefrom will 110 flow out of the tank at the top thereof, through a discharge outlet 60 connected with which outlet is a pipe 61, that conveys the air and vapor to the atmosphere or any desired point. Arranged within the chamber 115 58 is a baffle 62, which is preferably supported by means of arms or brackets 63, to extend across the outlet opening 59 and the baffle 62 is located intermediate the inlet 57 and outlet 59 of the chamber 58 so that the 120 steam entering the inlet opening 57 will strike the baffle 62 and any oil which is carried by the steam will be deposited upon the baffle 62, while the steam will pass around the baffle out of the opening 59 into the tank. The oil thus deposited upon the baffle will drip therefrom through an outlet opening 125 64 of the chamber 58 into a pipe 65, which latter has communication with the chamber 55. From the chamber 55 the oil will be 130

eventually carried away through the outlet pipe 56 with the surplus water flowing into the chamber 55 from the water receiving end of the tank 10.

5 It is thought that the operation of this improved apparatus will be clearly understood from the foregoing description, but briefly stated, it is as follows:

The aspirator or suction creating device 10 is submerged in the liquid in the chamber or receptacle 12 and is revolved at a suitable speed by the motor 26, thereby creating a suction due to the tangential mingling of the liquid and air between the vertical partitions, which divide the circumferential submerged space with intervals therebetween. The whirling motion thus created, prevents the liquid penetrating far into the circumferential space as the liquid after 15 flowing inward due to the partial vacuum created in the circumferential space and the natural pressure of the liquid behind the partition, the liquid is immediately caught by the following partition and thrown outward. In practice there is a constant inward and outward flow of liquid in the space between the periphery of the disks or in the outer spaces between the additional partitions. The action is enhanced by the breaking up 20 of the liquid into spray as it flows through the peripheral space and the entraining action of the liquid is effective to produce a vacuum, the intensity of the vacuum being determined by the velocity of revolution or depth to which the circular disks 25 are submerged.

The upright baffles 24^a are arranged concentrically with and in close proximity to the periphery of the aspirator and are provided for the purpose of breaking up or preventing the liquid from swirling in the chamber 12, and any number of these uprights or baffles may be provided.

While the intensity of vacuum obtainable 45 in the form herein shown, depends upon depth of submergence, rather than on speed of revolution, yet the volume of air sucked and discharged through the water is augmented by increasing the velocity of revolution, as well as by increasing the vertical 50 width of space between the upper and lower disks 22, 23. Where it is desirable that the vacuum produced shall not exceed a certain maximum, the condensation obtainable may 55 be regulated by the simple expedient of adjusting the depth or amount of water in the receptacle 12. The chamber or receptacle 12 is filled with water through the cold water pipe 35 and as the revolution of the 60 aspirator creates a suction as above described, this suction is manifested through the tube or pipe 21, drawing in air and condensation from the returns which are connected to the suction pipe 21 exteriorly of 65 the device. The air escapes through the out-

let opening 61 to the atmosphere. When the receptacle 12 is filled with water it overflows into the receptacle 14 and this latter is employed for the purpose of a heat insulator to prevent the water in the receptacle 12 from becoming too hot which would effect the efficiency of the aspirator.

When the receptacle 12 overflows and the receptacle 14 fills up with water, the latter overflows and drips down and is caught by the pans 29 which are filled up and overflow. The water eventually falls to the bottom of the tank and fills the heater until the float 33 operates and shuts off the water valve 34. The float then automatically maintains a water level which is predetermined. The water as it passes into the water chamber or accumulator in the tank finally passes through the filter and out of the discharge pipe 32. The receptacles 37, 43 serving to 80 collect all sediment and mud. When the tank overflows the water will pass out of the opening 53 into the discharge 56. As the water passes from the pans 31, it is broken up in fine streams by the serrated 85 edges of the pans and the incoming steam which is admitted into the inlet 59 strikes the streams of water to heat them and the steam at the same time is condensed. Any vapor or uncondensed steam and air finally 90 finds its way out of the tank through the opening 60.

With this improved construction, it will be manifest that a device of this character is admirably adapted to high pressure 100 plants, necessitating but a small space and dispenses with considerable piping and valves. As about eighty per cent. of the steam used in some systems can be condensed and purified, it is manifest that the 105 installation of a device of this character not only conserves the water but also conserves fuel. It will also be manifest that the aspirator by bringing into the heater the vapor and condensation from a "steam system" 110 will assist in heating the water within the heater.

The aspirator requires very little attention after having been once started in operation and it can be run indefinitely without materially affecting its efficiency.

What is claimed as new is:

1. An apparatus of the character described embodying a tank, a suction creating device in the upper portion thereof and having communication with a fluid passage, a filter in the tank at the bottom thereof, there being an outlet from the tank through which the liquid passes after passing through the filter, a series of trays arranged in the tank above the water level therein for receiving and breaking up the water from the suction creating device, means for supplying water to the suction creating device, and means for directing exhaust steam 130

through the streams of water from the said trays.

2. As a unitary structure a feed water heater embodying a tank, a mechanically operated suction creating device in the top of said tank and having communication with a fluid passage leading from the outside of said tank for creating a suction in the passage, said suction creating device operating to deliver the fluid from the passage into

heater, means intermediate the suction creating device and the filter for breaking up the liquid delivered from the suction creating device, and means for directing exhaust 15 steam through the liquid in the heater as the liquid is thus broken up.

In testimony whereof I have signed my name to this specification, on this 9th day of January, A. D. 1918.

EDWARD F. McCARTHY.
